UNITED STATES PATENT OFFICE.

ARTHUR H. BOSWORTH, OF WICHITA, KANSAS.

INHALER.

Application filed April 21, 1925. Serial No. 24,800.

This invention relates to inhalers for the medicinal treatment of the human respiratory organs, and for the administration of such substances as smelling salts, and the like, which are adapted for use by inhalation. An object of my invention is to reduce the number of parts, at the same time increasing the efficiency of the inhaler. A further object is to provide an inhaler of extremely simple, compact, light, convenient and efficient construction, which can be made more economically than has heretofore been possible. A further object is to provide a means of quickly and accurately controlling the quantity of medicament placed in each inhaler, at the same time so distributing the medicament as to expose the maximum surface for absorption by the passing air current. A still further object is to direct the flow of air in such a manner as to compel a maximum time of contact with the greatest possible surface of medicament, thus assuring efficient saturation.

The preferred embodiment of my invention is shown in the drawings. Fig. 1 is a perspective view of the receptacle, Fig. 2 is end view of same, Figure 3 a longitudinal cross section of the inhaler, Fig. 4 is an end view with portion cut away to show position of washer and filler, Figure 5 is a longitudinal view of the filler, and Fig. 6 an end view showing washer with filler outlined.

The receptacle may be of any desired shape or size, but is preferably formed of a hollow cylindrical tube, (1), one end of which is closed, the open end being partially closed and formed to suitably engage the nostril. This closing and forming may be accomplished in various ways, with or without cutting a portion of the tubing away, but is preferably accomplished by cutting a plurality of prongs, (3), so shaped that when bent over a partial closure is effected, leaving means of outlet (6) for the air, either through the central aperture or through a plurality of slots, or both. An opening or plurality of openings (2) is provided for inlet of air, these openings being preferably placed adjacent to the open end of the tube, so that one cap may effectively close all openings, and give complete protection from evaporation and ingress of dirt.

It is customary in designing inhalers to distribute the medicament in some manner to enlarge the extent of surface exposed to the air. This is sometimes accomplished by

diluting with paraffin or similar substances, which is open to the objection that free evaporation is retarded as soon as the surface medicament has evaporated; more often this is accomplished by sprinkling the medicament on some formless substance, such as cotton or excelsior; in my invention I have made use of an absorbent material of definite form, such as paper, which I call a filler (7), by means of which several valuable and distinct purposes are accomplished, among them the following: First, this filler is equally adapted to receive liquid medicaments, such as oils, or substances such as menthol which liquefy on warming; second, by increasing or reducing the extent or thickness of the filler a predetermined quantity of the medicament is absorbed; third, evaporation takes place from the surface only, and this surface may be more or less extended by altering the shape of the filler, to suit special requirements; fourth, in case of mixed medicaments of different boiling points, fresh medicament to replace surface evaporation is drawn from the interior substance of the filler by capillarity, rather than by evaporation of the more volatile constituents; the composition of the inhalation thus remaining practically constant at all times; fifth, by means of the definite form of the filler this serves not only the aforementioned purposes, but provides as well a division of the tube into chambers, (4 and 5), and means for properly dividing and directing the air currents.

I have shown the filler (7) in triangular form, but it is evident that variations of this form may be used. This filler is introduced into the tube in such a manner that the upper end is above the inlet opening or openings, (2), and free air space is left between the bottom of the filler and the closed end of the tube. The upper end of the chamber or chambers formed by the junction of the edges of the filler with the walls of the tube is then sealed by appropriate means, such as by turning down flaps integral with the filler, or by inserting a washer (8) in such a manner that the entering air is forced to first descend toward the bottom of the chamber or chambers (4) adjacent to inlet, then upward to point of outlet, thus bringing the air in contact with all surfaces of the filler before discharge. After the filler has thus been introduced and the chambers sealed as described, the prongs (3) are bent over as shown in Fig. 1 in order to hold the material

- within the container, and to provide a proper fit for the nostril. The cap is not an essential part of the inhaler, but is preferably placed over the end when not in use, to prevent evaporation and ingress of dirt, and the bead is provided as a shoulder for the cap to rest against. The container being made in one piece eliminates the possibility of coming apart and spilling contents, and is not easily refilled with inferior goods. Also, because of this structure and the particular uses of the filler as before described this inhaler comprises fewer and simpler parts, and can be filled more rapidly than others.
- It will be evident that the particular size and shape of the tube, filler, and prongs, and the final shape when assembled are not material to the invention, various modifications in the form, arrangement, and construction

being possible and still be within the spirit of the invention.

What I claim is:

An inhaler, comprising a casing, consisting of a single piece constituting a tubular body portion closed at one end and having inherent integral prongs at the other end, the edges of which are in spaced relation, in combination with an absorbent filler within the body portion, the filler consisting of a flat strip of medicated absorbent carrying material bent angularly longitudinally of the strip with the edges of the angular filler frictionally engaging the inner wall portion of the casing to divide the space in the casing into a central passage-way and a plurality of passage-ways surrounding the first named passage-way.

ARTHUR H. BOSWORTH.
